UNITED STATES PATENT OFFICE

JOHN W. PARKER, OF WEST BARRINGTON, RHODE ISLAND, ASSIGNOR TO BROWN & SHARPE MANUFACTURING COMPANY, OF PROVIDENCE, RHODE ISLAND, A CORPORATION OF RHODE ISLAND

INSIDE CALIPER

Application filed March 26, 1928. Serial No. 264,599.

This invention relates to an improved construction of inside caliper; and has for its object to provide such a caliper with an extendible cross head having measuring members slideable one within the other and having an operating handle, and to also provide stop means independent of the handle for preventing complete separation of its relatively slideable members one from the other when the handle is disengaged from the head.

10 A further object of the invention is the provision of an inside caliper formed of a cross head having tubular telescoping parts with a spring housed within these parts for pressing them toward extended position also providing a collar on the outer tube to which a handle is detachably connected and having a binding pin in the handle arranged to bind the head parts in different adjusted positions.

15 With these and other objects in view, the invention consists of certain novel features of construction, as will be more fully described, and particularly pointed out in the appended claims.

20 In the accompanying drawings:

Fig. 1 is a side elevation illustrating my improved construction of caliper.

Fig. 2 is a sectional view of the caliper.

25 Fig. 3 is an enlarged view showing the construction of the telescoping measuring head and the means for limiting the extending stroke of the movable member independent of the binding action of the handle.

Fig. 4 shows the inner tubular telescoping member as provided with a longitudinal groove with end walls.

30 Fig. 5 is a modification illustrating a stop pin formed in the outer tube and extending into the groove in the inner tube to serve as a stop to limit the extending action of the extension member.

It is found in the practical construction and operation of inside calipers of the cross head type, of advantage to provide means 35 whereby the telescoping parts of the cross head will not be completely separated when the operating handle is removed from the cross head as it is found in practice of advantage to so construct the caliper that the handle may be removed both for convenience

for storage and shipment and also so that the handle may be used on measuring heads of other sizes thereby eliminating the necessity of forming a handle for each and every head of a set; and to accomplish this in a simple 55 and effective way, I have provided a cross head having telescoping tubular members pressed toward extended position by a spring inclosed in the tubes, and to the outer tube I have applied a collar to which an operating handle is removably attached and I have also provided a simple stop member independent of the handle which extends into a groove in the inner tube having end walls whereby this stop is arranged to operate independently of the retaining means in the handle permitting the handle to be completely removed to reduce the storing space and also permitting a single handle to be used on any of the different sized heads of a set; and 60 the following is a detailed description of the present embodiment of my invention and showing one means by which these advantageous results may be accomplished.

With reference to the drawings, 10 designates the outer tube of the cross head which is closed at one end as at 11. Near the opposite end of this tube is secured a collar member 12 preferably by being forced thereon.

80 This collar is also preferably provided with a threaded stem 13 on to which the tubular handle 14 is screwed. Slidably mounted within this outer tube is an inner telescoping tube 15 also closed at its outer end as at 16, and provided on its outer surface with a longitudinally disposed groove 17 having opposite end walls 18.

Within these inner and outer tubes is mounted a coil spring 19 in one end of which is mounted the guide pin 20 having a head 21 at one end resting against the closed end 11 of the tube 10 and extending up inside of the spring to assist in retaining it in axial alignment with the inner tube. This spring 85 operates within these inner and outer tubes to press them relatively toward extended position.

90 In order to limit the outward motion of this inner tube within the outer tube, I have 100

provided a set screw 22 which is threaded into the collar member to bind against the outer tube, the screw being also provided with a reduced portion 23 which extends thru the 5 outer tube into the groove 17 to engage the end wall 18 of the inner tube and so limit the relative outward motion of the inner tube and prevent it from being forced out of the inner tube when released by the binding 10 action of the mechanism presently described. In some instances instead of using the screw 22 I may employ a separate pin 30 to serve as a stop for the inner tube.

The operating handle 14 is preferably of 15 tubular construction and is threaded internally at its inner end as at 24 to screw onto the stem 13 of the head member 12 and this tubular handle is also internally threaded at its outer end as at 25 for the reception of the 20 adjustable plug 26 which is threaded therein.

Within this tubular handle, I mount a binding pin 27 one end of which extends loosely into the bore in the plug 26 while its opposite end 28 extends thru the stem 13 and 25 the wall of the outer tube 10 into engagement with the inner tubular extension member 15, whereby when the handle portion 29 of the plug 26 is rotated to screw it inwardly this pin 27 is caused to bind the inner tube 15 and retain it in the desired adjusted position and when rotated and screwed outwardly it releases this pin to permit a free relative endways movement of the inner tube 15.

My improved construction of inside caliper 35 may be manufactured at a low cost and by the use of a stop member which is independent of the handle and its binding action, I am enabled to remove the handle from the measuring head to reduce to the minimum 40 the space required for storing and for shipment and also to permit this single handle to be used on any one of a set of heads of different sizes without the necessity of having a handle for each head.

45 The foregoing description is directed solely towards the construction illustrated, but I desire it to be understood that I reserve the privilege of resorting to all the mechanical changes to which the device is susceptible, 50 the invention being defined and limited only by the terms of the appended claims.

I claim:

1. An inside caliper comprising a measuring cross head formed of a plurality of tubular members one being slidable within the other, a spring within the tubes pressing them toward extended position, a handle detachably connected to one of said members, means in the handle for retaining said members in adjusted position, and means independent of the retaining means in the handle for limiting the extending motion of the tubes.

2. An inside caliper comprising a measuring 65 cross head formed of tubes slidable one

within the other, a spring in the tubes pressing them toward extended position, a collar on the outer tube having a threaded stem portion, a tubular handle threaded onto the stem, a binder pin in the handle, a member adjustably mounted at the outer end of the handle for causing said pin to bind the slidable tubes in adjusted position, and a stop member in said collar extending into engagement with one of said slidable tubes arranged to prevent complete separation of the tubes when the handle has been disconnected from the collar.

3. An inside caliper comprising a measuring cross head formed of two tubes slidable one within the other, a spring in the tubes pressing them toward extended position, a collar on the outer tube having a threaded stem portion, a tubular handle detachably connected to the stem, a binder pin extending substantially the length of the handle, a member adjustably mounted at the outer end of the handle for causing said pin to bind the head parts in adjusted position, said inner tube having a longitudinal groove with end walls, and a screw in the collar extending thru the outer tube into said groove in the inner tube to prevent complete separation of the tubes when the handle has been disconnected from the head.

4. An inside caliper comprising a measuring cross head formed of two tubular members, one slidable within the other, a spring in the tubes pressing them toward extended position, a collar fixed to the outer tube having a threaded stem portion, a tubular handle threaded onto the stem, an elongated binder pin in the handle, a plug threaded into the outer end of the handle arranged to cause said pin to bind said tubular members in adjusted position, and a stop member independent of said binding pin to prevent a complete separation of the telescoping parts when the handle is removed.

5. In an inside caliper, an extendible measuring cross-head including two tubular members slidable one within the other, an operating handle detachably connected to said cross-head, means movable in said handle and engageable with the inner member to releasably retain said members in different adjusted positions, and cooperating stops on said members limiting the relative movement of said members to prevent complete separation when the handle with the retaining means therein is detached from said cross-head.

6. In an inside caliper, an extendible measuring cross-head including two tubular members slidable one within the other and a collar on the outer tube, an operating handle detachably connected to said collar, means movable in said handle and engageable with the inner member to releasably retain said inner member in different adjusted positions.

in the outer member, and cooperating stops on said members limiting the relative movement of said members to prevent complete separation when the handle with the retaining means therein is detached from said collar.

7. In an inside caliper, a measuring cross-head having a plurality of relatively slideable members one within the other and spring means yieldingly urging the members to relatively extended position, a handle connected to said cross-head, means in the handle movable to retain the members in adjusted relative position, and stop means in said cross-head independent of the retaining means for limiting the relative extension of said members.

8. In an inside caliper, a measuring cross-head having a plurality of relatively slideable members one within the other and spring means yieldingly urging the members to relatively extended position, a handle detachably connected to said cross-head, means in the handle movable to retain the members in adjusted relative position, and stop means in said cross-head independent of the retaining means for limiting the relative extension of said members upon detachment of said handle and the retaining means therein from said cross-head.

In testimony whereof I affix my signature.
JOHN W. PARKER.
